DRIVE-IN THEATRE TOY

Saul Robbins, West Orange, and Isaac Heller,
Scotch Plains, N.J.

Application September 14, 1959, Serial No. 57,537

Term of patent 14 years

(Cl. D34—15)

Figure 1 is a perspective view of a drive-in theatre toy, showing the new design and viewing it from the front and one side thereof;

The dominant features of my design reside in the portions shown in full lines. The vehicles shown in broken lines in Fig. 1 are for illustrative purposes only.

We claim:

The ornamental design for a drive-in theatre toy, as shown and described.
